UNITED STATES PATENT OFFICE.

HENRY HOVLAND, OF EAST ORANGE, NEW JERSEY, ASSIGNEE TO WESTERN ELECTRIC COMPANY, INCORPORATED, OF NEW YORK, N. Y., A CORPORATION OF NEW YORK.

REGISTERING SYSTEM.

1,291,894.

Specification of Letters Patent. Patented Jan. 21, 1919.

Application filed April 26, 1917. Serial No. 164,655.

To all whom it may concern:

Be it known that I, HENRY HOVLAND, a citizen of the United States, residing at East Orange, in the county of Essex and State of New Jersey, have invented certain new and useful Improvements in Registering Systems, of which the following is a full, clear, concise, and exact description.

This invention relates to registering and recording mechanism, more particularly for registering mechanism which may be employed in telephone systems.

The object of this invention is the provision of means which will accurately register or record signals resulting from rapidly recurring current impulses.

In accordance with the general features of this invention there are provided two sets of relays responding to the current impulses constituting the signals, one set of said relays being designed and adjusted to release quickly and adapted to release upon the break of the impulse circuit; the other set of relays being designed and adjusted to energize very rapidly and connected in circuit to operate from the closure of the circuit. These sets of relays control the operation of a group of controlling relays, which group of relays in turn control the setting of the registering and recording device.

The drawing diagrammatically represents a portion of a telephone system employing the present invention. Only so much of the system is disclosed as is necessary for a clear understanding of this invention.

In this disclosure reference is made to a line finder. It will be understood, however, that any suitable means may be employed for seizing the calling line and extending it to the means which controls the setting of the registering mechanism.

An impulse transmitter suitable for use in the present system is disclosed in applicant's Patent No. 1,271,164, issued July 2, 1918.

The registering or recording mechanism which will hereinafter be referred to as the register, and which is generally designated R in the drawing, consists of a shaft 1

mounted in any suitable manner for rotation. At one end of this shaft and extending at right angles thereto, there is secured an arm 2 which, when unrestrained, moves in a clockwise direction under the control of the spring 3. The arm 2 is held in its normal position by a latch member 4 pivotally mounted at the free end of the arm 2. The latch member 4 is normally held in alignment with the arm 2 by a spring member. This latch member is provided with an arm 5, which engages a hook 6 of the armature of the magnet 86 to hold the arm 2 in its normal position. For controlling the setting of the arm 2 there are provided five rods designated 8, 9, 10, 11 and 12. Each of these rods is substantially similar in structure and operation, so it will only be necessary to describe the structure, mounting, and operation of one rod, for example, the rod 12. The rod 12 is mounted for rotation in any suitable manner, and near one of its ends is provided with a right-angular pin 13. This pin operates in the bifurcated extension of the pivoted armature 14, which is mounted for actuation under the control of either of the magnets 15 or 16. When the magnet 15 is energized it attracts its armature to move the pin 13 in a downward direction. This causes the rod 12 to rotate in a counter-clockwise direction. When, however, the magnet 16 is energized, it attracts its armature to move the pin 13 in an upward direction. This causes the rod 12 to be moved in a clockwise direction, as indicated by the arrow. The rod 12 is provided with a plurality of stops, two for each register; these stops are indicated at 17 and 18. It will be noted that stops 17 and 18 are out of alignment. An arc-shaped member 19 provided with ratchet teeth on its inner surface is engaged by dog 20 on the latch member 4 to hold arm 2 in actuated position as will be further described in the operation of the system.

Mounted on the shaft 1 of the register, there are secured a plurality of contact controlling devices of the structure and arrangement of the sequence switch disclosed

in the patent to Reynolds and Baldwin 1,127,808. These contact elements of the registers R¹, R² and R³ are diagrammatically indicated at 102, 103 and 104, respectively. 5 These registers may be restored by power driven means as in the above noted patent.

With this brief description of the apparatus it is believed that the invention will best be understood by setting up a number 10 on the registers shown. Let it be assumed that the desired number which is transmitted from the dial switch at the substation apparatus is the number 109. When the subscriber removes his receiver from the 15 switchhook, the hook-switch springs 21 and 22 are closed. As soon as the receiver is removed from the switchhook, the line finder which is indicated by the brushes 27 and 28 is operated in the well-known manner to seize the terminals 29 and 30 of the 20 calling line. As soon as the calling line has been located, a circuit is completed from ground, through the winding of the relays 23 and 24 in parallel, conductor 25, brush 28, terminal 30, switchhook springs 22 and 21, contact 31, shunting spring 32, transmitter 33, winding of the induction coil 34, impulse spring 35, contact 36, terminal 29 of the calling line, finder brush 27, armature and back contact of the cut-off relay 38, armatures and back contacts of the 30 relays c¹, c², c³, c⁴, c⁵, c⁶, c⁷, c⁸, c⁹, lower winding of relay 40, to grounded battery, whereupon relays 23, 24 and 40 are energized. 35 The relay 23 at its left-hand armature and front contact completes a circuit from grounded battery, winding of the relay 38, contact and left-hand armature of relay 23, finder brush 27, terminal 29, contact 36, impulse spring 35, winding of induction coil 34, transmitter 33, shunting spring 32, contact 31, switchhook springs 21 and 22, terminal 30, finder brush 28, conductor 25, winding of relay 23, to ground. At the 40 right-hand contact and armature of the relay 23 a circuit is completed from ground, conductor 41, armature and back contact of relay 42, winding of the relay 43, to grounded battery. The relay 43 attracts its armatures and at its left-hand armature and front contact completes a circuit from ground, conductor 44, right-hand armature and back contact of relay C⁹, right-hand winding of relay c⁹, to grounded battery, 45 and similar parallel circuits are completed through the right-hand armatures and back contacts of the relays C⁸, C⁷, C⁶, C⁵, C⁴, C³, C² and C¹, to grounded battery, through the right-hand windings of relays c⁸, c⁷, c⁶, c⁵, c⁴, c³, c², c¹. The last-mentioned relays are 50 energized in these circuits.

As soon as the dial D is moved, the circuit through contact 31 and shunting spring 32 is opened, and a circuit is completed

through contact 45 and shunting spring 32. 65 The closing of the circuit through contact 45 and shunting spring 32 includes the resistance 46 in the energizing circuit of the relay 23. The relay 23 is marginal and does not remain energized in series with resistance 46. When the dial is moved farther, the circuit completed through the contact 36 and spring 35 is opened, but the relay 24 is slow to release and does not deenergize 70 during the momentary interruptions of its operating circuit. The deenergization of relay 23 causes relay 38 to release and also causes the shunting circuit about relay 42 to be broken. The relay 42 is energized over a circuit extending from grounded battery, 75 windings of the relays 43 and 42, right-hand contact and armature of the relay 43, front contact and armature of relay 24 to ground. When, in the operation of the dial, the 80 spring 35 engages the contact 36, a circuit 85 is closed from ground, winding of relay 23, conductor 25, finder brush 28, terminal 30, switchhook springs 22 and 21, resistance 46, contacts 32 and 45, spring 35, contact 36, terminal 29, brush 27, armature and back 90 contact of cut-off relay 38, armature and front contact of relay c¹, and winding of this relay to grounded battery and in parallel through the left-hand winding of the relay C¹, to grounded battery. Relay C¹ attracts its armatures and at its right-hand 95 armature and back contact interrupts the holding circuit of the relay c¹. At the right-hand contact and armature of relay C¹ a holding circuit is closed for this relay which may be traced from ground at the left-hand armature and front contact of relay 43, conductor 44, right-hand armature and front contact of relay C¹, contact 62, spring 61, resistance 93, to grounded battery. Since 100 the relay 23 is marginal it will not energize while resistance 46 is connected in this operating circuit. When now the dial is operated to again interrupt the circuit through contact 36 and impulse spring 35, 105 relay c¹ will retract its armature and at its back contact will extend this circuit to the relay c². At the close of the series of the impulses corresponding to the first digit, 110 the dial will return to its normal position to close the contact 31 and shunting spring 32.

With the contact 31 and shunting spring 32 in engagement, the resistance 46 is shunted from the operating circuit of the relay 23, 115 causing this relay to energize. The relay 23 attracts its armatures and completes a circuit from ground, its right-hand armature and front contact, conductor 41, armature and front contact of relay 42, contacts 26 and 47, winding of relay 48, to grounded battery. Relay 48 attracts its armatures and completes a locking circuit for itself from its 120

front contact and left-hand armature over the remainder of the circuit just described. When the relay 48 is energized a circuit is completed from grounded battery, armature 5 and contact 49 of this relay, winding of relay 50, conductor 51, left-hand armature and front contact of relay C^1 , right-hand armature and back contact of relay C^1 , conductor 44, left-hand front contact and armature of relay 43, to ground, when relay 50 is energized, to rotate the rod 54 in a clockwise direction. The armature of magnet 50, in operating, closes a circuit from ground, spring 52 and its contact, conductor 53, winding of magnet 55, contact 56, right-hand armature of relay 48, to grounded battery. The magnet 55 attracts its armature and in so doing disengages the hook 6 from the hook 5 of the latch member, allowing the arm to rotate until it engages the stop member 57. As soon as the latch member 4 engages the stop or pin 57, since the latch member is pivotally mounted on the arm 2, the pawl 20 is thrown into engagement with the teeth of the ratchet member 19. The armature of magnet 55 in operating closes a circuit from grounded battery, contact and spring 58, conductor 59, winding of the relay 60, spring 61, contact 62, right-hand winding of the relays C^1 and C^2 , right-hand front contact and armatures of these relays, conductor 44, right-hand front contact and armature of relay 43, to ground. Relay 60 attracts its armatures and establishes a locking circuit for itself from ground, resistance 63, upper armature and contact spring 61, winding of relay 60, conductor 59, contact spring 58 and its contact, to grounded battery. The relay 60 when it attracted its armature opened the holding circuit of the relays C^1 and C^2 at contact 62 and contact spring 61. At the left-hand front contact and armature of relay C^2 the energizing circuit of magnet 50 is opened, causing this magnet to deenergize and permit the rod 54 to return to its normal position. When the rod 54 returns to its normal position, the energizing circuit of magnet 55 is opened at contact spring 52 to cause the magnet 55 to deenergize. When the magnet 55 deenergizes, the contact spring 58 disengages its contact to open the energizing circuit of the relay 60. At the time that the relays C^1 and C^2 deenergized they completed circuits at their right-hand armatures and back contacts for reenergizing relays c^1 and c^2 . The relays are now in the following condition: relays 42, 43 and 48, relays 23 and 24, cut-off relay 38, the relays c^1 , c^2 , c^3 , c^4 , c^5 , c^6 , c^7 , c^8 and c^9 are energized.

On operating the dial to transmit the impulses corresponding to the second digit of the desired number, which is zero, the shunting spring 32 and its contact 31 are disengaged and the impulse spring 35 and its contacts 36 are also disengaged, causing the relay 23 and the cut-off relay 38 to release. The relay 23 at its right-hand armature and front contact interrupts the actuating circuit of relay 48, allowing it to release. When now, the impulse spring 35 engages its contact 36 the relay C^1 will be energized. On releasing the dial, shunting spring 32 will engage its contact 31, to short-circuit the resistance 46, and cause the relay 23 to operate. It will be remembered that the register R^1 is in position 1. With the register R^1 in position 1 and relay 23 energized a circuit is completed from ground, conductor 41, armature and front contact of relay 42, armature and back contact of relay 48, contacts 64 and 65, contacts 67 and 68, winding of the relays 69, to grounded battery. Relay 69 attracts its armatures; this completes a circuit from grounded battery, contact 70, conductor 72, winding of magnet 16, conductor 78, left-hand armature and front contact of the relay C^1 , right-hand armature and back contact of relay C^2 , conductor 44, left-hand front contact and armature of relay 43, to ground. The relay 16 attracts its armature and by so doing rotates the rod 75 in a clockwise direction. Simultaneously the magnet 71 is actuated to release the arm 2^a. The arm 2^a rotates until it engages the positioned stop 76. The energizing circuit of magnet 71 extends from grounded battery, contact 101, winding of magnet 71, conductor 90, contact and contact spring 73 to ground. When the magnet 71 attracted its armature, the contact spring 79 engaged its contact and closed a circuit from grounded battery, conductor 59, winding of the relay 60, contact spring 61, contact 62, right-hand winding of relay C^1 , right-hand front contact and armature of this relay, conductor 44, left-hand front contact and armature of relay 43, to ground. Relay 60 again attracts its armature and thereby completes a locking circuit for itself from ground, resistance 63, upper armature and contact spring 61, winding of the relay 60, to grounded battery. Relay 60 when it attracts its armature causes the deenergization of any of the relays C^1 to C^9 which have been actuated. When the relay C^1 retracts its armature, the energizing circuit of the magnet 16 is interrupted, causing this magnet to retract its armature, thus permitting the rod 75 to return to normal.

The subscriber now sends the next series of impulses corresponding to the units digit, which in the case assumed is 9. In response to each of these impulses a relay corresponding to the relay C^1 is energized and locked up, while a relay corresponding to relay c^1 is deenergized. At the termination of the line impulses the relays C^1 to C^9

4 and relay 40 will be actuated and locked up and the relays C^1 to C^9 will be deenergized. When now the resistance 46 is shunted from the operating circuit of the relay 23, a circuit is completed from ground, right-hand armature and front contact of the relay 23, conductor 41, armature and front contact of relay 42, armature and back contact of relay 48, contacts 64 and 65, armature and 10 back contact of the relay 69, contacts 80 and 81, contacts 82 and 83, winding of the relay 84, to grounded battery. Relay 84 attracts its armatures and establishes a locking circuit for itself by way of its right-hand front contact and armature over the circuit just described. At the right-hand armature and contact of relay 84 a circuit is completed from grounded battery, armature of relay 84 and contact 85, conductor 20 72, winding of magnet 15, conductor 87, lower front contact and armature of relay 40, armature and back contact of relay 60, to ground. Magnet 15 is energized in this circuit. Magnet 15 rotates the rod 75 in 25 a clockwise direction to set the stop 88. The armature of magnet 15 is operated and closes a circuit from ground, spring 89 and its contact, conductor 90, winding of magnet 86, contact 91, right-hand armature of 30 relay 84 to grounded battery. The magnet 86 is energized and unlatches the arm 2 of register R^3 , permitting this arm to rotate until it engages the stop 88. The armature of the relay 86 in operating closes a circuit 35 from grounded battery, contact and spring 92, conductor 59, winding of the relay 60, contact 61, contact spring 62, through the winding of relays C^1 to C^9 , the right-hand front contacts and armatures of these relays, conductor 44, to ground at the left-hand front contact and armature of relay 43. Relay 60 attracts its armature and at the contact spring 62 interrupts the holding 40 circuits of the relays C^1 to C^9 .

45 It will be understood that as many registers of the type of register R will be employed as there are digits in the desired number. For registering a number of more than three units, it will only be necessary to increase the number of registers and lengthen rods 8 to 12 and provide them with the necessary stops for each register. In the description of this invention it has been deemed necessary only to describe the 50 setting of the registers. In the employment of this invention in a telephone system after the registers have been set they may be used to govern the operation and setting of counting relays, which in turn 55 control the setting of automatic switches in the manner clearly shown and described in the patent to A. E. Lundell, 1,168,319. When it is desired to erase the number registered the subscriber replaces the receiver

on its switchhook. This causes the separation of the switchhook springs 21 and 22 and, in turn, the deenergization of the relay 24. Relay 24 on deenergizing at its front contact and armature interrupts a circuit which maintained the relay 43 energized. The relay 43 at its left-hand back contact and armature closes a circuit from ground, conductor 94, contact 95, winding of the motor magnet 96 to grounded battery, and in parallel through contact 97, winding of motor magnet 98 to grounded battery, and contact 99, winding of the motor magnet 100 to grounded battery. The motor magnets operate in the manner of the sequence switches to restore the registers R^1 , R^2 and R^3 to their normal position, in which they will be held by hook 6. 65

What is claimed is:

1. In a registering system, a multi-position switch, a counting device including a series of counting relays for directly controlling the operation of said switch, and means including fast and slow operating relays for setting said counting device, said means being variably and directly controlled from a distant point. 25
2. The combination with a telephone line, a variably controlled impulse transmitting device for transmitting series of impulses associated therewith, of a group of relays normally deenergized, a second group of relays which is normally energized, means responsive to said impulses for reversing the condition of certain of the relays of said groups, a counting device operated under the control of said groups of relays, and a multi-position switch arranged to be positioned in accordance with the setting of said counting device. 95
3. In a telephone system, a telephone line, a variably operable impulse transmitting device associated therewith, a series of counting relays responsive to the impulses from said impulse transmitting device, and a register switch positioned in accordance with the operation of said counting relays to selectively control other devices. 100
4. In a telephone system, a telephone line, a variably operable impulse transmitting device associated therewith, a counting device arranged to be set by said impulse transmitting device, a plurality of registering devices for selectively controlling other devices, and means operated in response to the setting of said counting device for starting and stopping said registering devices. 115
5. In a telephone system, a telephone line, a variably operable impulse transmitting device associated therewith, a plurality of registering devices for selectively controlling other devices, means for starting and common means for stopping said registering devices, a counting device arranged to 120
- 125

- be operated under the control of said impulse transmitting device, and means governed by said counting device for controlling said starting and said stopping means.
- 5 6. In a telephone system, a telephone line, a variably operable impulse transmitting device associated therewith, a plurality of registering devices, means for starting and common mechanical means for stopping said registering devices, a counting device arranged to be operated under the control of said impulse transmitting device, and means governed by said counting device for controlling said stopping means.
- In witness whereof I hereunto subscribe my name this 21st day of April, A. D. 1917.

HENRY HOVLAND.
